MOTOR-CONTROL SYSTEM.

1,242,910.

Specification of Letters Patent.

Patented Oct. 16, 1917.

Application filed August 6, 1915. Serial No. 43,994.

To all whom it may concern:

Be it known that I, HOWARD L. BEACH, a citizen of the United States, and a resident of Edgewood Park, in the county of Allegheny and State of Pennsylvania, have invented a new and useful Improvement in Motor-Control Systems, of which the following is a specification.

My invention relates to motor-control systems, and it has for its object to provide a simple and effective means for controlling the speed of electric motors during their acceleration, operation and retardation.

Motor-control systems of the same general character as that of my invention have, heretofore, been provided with series and shunt controlling circuits which comprised resistors to be so controlled as to vary the speed of the motors between desired limits. In such arrangements, it has been necessary to provide switching mechanisms of a somewhat complicated nature to control the resistors. It has been customary, also, to decrease the resistance of either of the controlling circuits by shunting the resistors included therein.

In accordance with the present invention, I provide a plurality of resistors which are connected in shunt relation to the motor armature. The usual series or starting resistor is controlled by accelerating switches in the usual manner. By means of a simple arrangement, the shunt resistors are successively transferred from the shunt circuit to a series connection in parallel with the starting resistor. The effect is to gradually increase the resistance of the shunt circuit and to decrease the resistance in series with the armature winding. By properly arranging the several circuits, the speed of the motor may be controlled as desired and the motor may be caused to operate uniformly at relatively low speeds.

In the accompanying drawings, Figure 1 is a diagrammatic view of circuits and apparatus embodying my invention. Fig. 2 is a diagrammatic view of a schematic arrangement of the system of Fig. 1. Figs. 3, 4, 5, 6 and 7 are diagrammatic views illustrating the circuits as arranged in accordance with successive positions of the controller.

Line conductors 1 and 2, which may be connected to any suitable source of direct current, supply energy to an electric motor 55 having an armature winding 3 and a shunt

field winding 4. A shunt circuit for the armature winding comprises resistors 5, 6 and 7 which are adapted to be connected in parallel with each other. The connections of the resistors 5, 6 and 7 are respectively controlled by electromagnetic switches 8, 9 and 10, each of which is provided with a shunt actuating coil 11.

A sectional starting resistor 12, which is in series with the motor armature, is controlled by a series of progressively actuated switches 13, 14 and 15. The switch 13 is provided with a shunt actuating coil 16 while the switches 14 and 15 are provided with series actuating coils 17. Each of the switches for controlling the resistor 12 is provided with series holding coils 18, each of which, except that of switch 15, is in series with the actuating coil 17 of the succeeding switch to close.

A controller 19, or master switch, comprises a contact segment 20 which successively engages a plurality of contact members 21 for producing the operation of the several electromagnetic switches in their proper sequence, as will be later described.

To start the motor, a line switch 22 is first closed. The controller handle is then actuated to the left, as viewed in Fig. 1, to engage the first contact member 21 and thereby complete a circuit comprising the actuating coil 23 of a main switch 24. The latter then closes to complete the armature circuit for the motor which extends from the positive line conductor 2 through line switch 22, main switch 24, armature winding 3, starting resistor 12, and main switch 22 to line conductor 1. A low-resistance shunt circuit for the armature winding 3 comprises the resistors 5, 6 and 7 which are connected in parallel with each other. The electrical connections that are established by the controller in its first position are diagrammatically shown in Fig. 3. The motor then operates at a low rate of speed, because of the low-resistance shunt circuit for the armature.

In the second position of the controller, the coil 11 of the electromagnetic switch 8 is energized to actuate the latter to its upper position and thereby disconnect the resistor 5 from the shunt circuit and connect it in series with the armature winding 3 but in parallel with the resistor 12. The several circuits are now arranged in accordance with

the diagram of Fig. 4. The removal of the resistor 5 from the shunt circuit operates, in effect, to increase the resistance of the shunt circuit and thereby cause an increased current to traverse the motor winding. The connection of the resistor 5 in parallel with the resistor 12 serves to decrease the resistance of the series circuit and thereby accelerate the motor.

- 10 The actuation of the controller to its third and fourth positions operates, in a similar manner, to successively transfer the resistors 6 and 7 from the shunt circuit to the series circuit, the resistors 6 and 7 being connected in parallel with the resistors 12 and 5 and with each other. The circuits obtaining in the respective positions of the controller 19 are illustrated in Figs. 5 and 6. The resistance of the shunt circuit is 15 gradually increased, and the resistance of the series circuit is gradually decreased, by the changes in connections above described, and the motor speed is increased to a corresponding degree.
- 20 The actuation of the controller arm 19 to its final position completes a circuit for the actuating coil 16 of switch 13. The latter then closes to complete a circuit through the holding coil 18 and the actuating coil 17 of switch 14 for shunting one of the sections 25 of the resistor 12. The switches 14 and 15 then close in order to complete a shunt circuit for the resistor 12 and thereby further accelerate the motor to its normal speed.
- 30 The shunting of the resistor 12 operates to establish a shunt circuit for the resistors 5, 6 and 7.
- 35

When it is desired to reduce the speed of the motor, the controller handle may be actuated in the opposite direction to that previously described and allowed to remain at any intermediate position. It will be noted that the resistor 12 is shunted during the operation of the motor, since the holding coil 18 of switch 15 is in series with the motor armature. The return of the controller arm toward its illustrated or inoperative position will not operate to insert the resistor 12 in series with the motor armature until the 40 main switch 24 is opened to break the circuit of the coil 18.

45 When the controller arm is in its third position, the circuit of the actuating coil 11 of the switch 10 has been opened, and the latter assumes its illustrated position to disconnect the resistor 7 from the series circuit and connect it in parallel with the motor armature. The counter-electromotive force of the motor then causes current to traverse the shunt circuit thus established, and the 50 speed of the motor is accordingly decreased. In a similar manner, when the controller is actuated to its second and first positions, the resistors 6 and 5 are successively transferred 55 from the series circuit to the shunt circuit

and are again connected in parallel with each other. The reduction of resistance in the shunt circuit causes an increased current to traverse it, and the speed of the motor is reduced in a corresponding degree.

70 When the shunt circuit comprises the resistors 5, 6 and 7 connected in parallel with each other, the motor operates uniformly at a comparatively low rate of speed. This condition is especially desirable in connection with hoists, elevators and similar machines in which it is desirable to operate at a low rate of speed before the motor is brought to a stop. To stop the motor, when it is operating under the conditions just described, it is only necessary to return the controller to its "off" position. The motor then operates as a generator, and current traverses the shunt circuit comprising the resistors 5, 6 and 7 to effect the dynamic 75 braking of the motor.

To bring the motor quickly to rest when it is operating at a comparatively high rate of speed, the controller handle may be returned to its "off" position, through the 80 various intermediate positions, to successively connect the resistors 5, 6 and 7 in the shunt circuit and to open the main switch 24. The dynamic braking action, which is thereby produced, may be graduated by adjusting the controller in accordance with the 85 motor speed, or the maximum effect may be obtained by returning the controller to its "off" position to reduce the resistance of the dynamic braking circuit to a minimum.

100 In the operation of the system as above described, it will be noted that the circuits of the shunt-connected resistors are not merely opened to increase the resistance of the shunt circuit, but are transferred bodily from one 105 circuit to another by means of double-throw switches. By means of the arrangement above described, I am enabled to gradually accelerate the speed of the motor and to cause the latter to operate at various speeds 110 corresponding to the arrangement of the several circuits. I am further enabled to bring the motor safely and gradually to rest or, in case of emergency, to employ a dynamic braking action, the effect of which is 115 within the control of the operator.

120 While the motor embodied in the control system has been shown and described as operating in one direction only, it will be obvious that the principle of my invention is 125 equally applicable to a motor provided with reversing means such as is commonly employed in connection with elevators, hoists and similar machines. It is understood that such changes may be made, without departing 130 from the spirit of my invention, as fall within the scope of the appended claims.

135 I claim as my invention:

1. In a motor-control system, the combination, with an electric motor, and a plu 140

rality of resistors in parallel relation to the armature of said motor, of means for successively connecting said resistors in series relation to the motor armature and in 5 parallel relation to each other.

2. In a motor-control system, the combination with an electric motor, and a plurality of resistors in parallel relation to the armature of said motor and in parallel relation to each other, of means for successively connecting said resistors in series relation to said armature and in parallel relation to each other.

3. In a motor-control system, the combination with a shunt-wound electric motor, a resistor in series relation to the motor armature, and a second resistor in parallel relation to said armature and in series relation to the other resistor, of means for 20 successively connecting the second resistor in series with the motor armature and in parallel relation to the other resistor and shunting said other resistor.

4. In a motor-control system, the combination with a shunt-wound electric motor and a resistor, of means operable, according to its position, to connect said resistor either in parallel or in series relation to the armature of said motor, and means for controlling said connecting means.

5. In a motor-control system, the combination with an electric motor, and two circuits that are respectively in series and in parallel relation to the armature of said 35 motor and in series relation to each other, of a resistor, and means for transferring said resistor from one circuit to the other.

6. In a motor-control system, the combination with a shunt-wound electric motor, 40 and two circuits that are respectively in

series and in parallel relation to the armature of said motor, of a resistor in each of said circuits, and means for successively transferring one of said resistors from the one circuit to the other in parallel relation 45 to the other resistor and shunting said other resistor.

7. In a motor-control system, the combination with an electric motor having an armature and a field-magnet winding, and 50 two circuits that are respectively in series and in parallel relation to said armature and in series relation to each other, of a resistor in each of said circuits, and means for controlling one of said resistors whereby it 55 is transferred to the other circuit in parallel relation to the other resistor.

8. In a motor-control system, the combination with an electric motor, a resistor in series relation to the armature of said 60 motor, a plurality of resistors in parallel relation to said motor armature and to each other, of means for successively connecting each of said parallel-connected resistors in parallel relation to said series-connected resistor.

9. In a motor-control system, the combination with an electric motor, a resistor in series relation to the armature of said motor, a plurality of resistors in parallel 70 relation to said motor armature and to each other, of means for successively connecting each of said parallel-connected resistors in parallel relation to said series-connected resistor and for shunting said series-connected 75 resistor.

In testimony whereof, I have hereunto subscribed my name this 21st day of July, 1915.

HOWARD L. BEACH.
